(57) **CLAIM**

The ornamental design for a liner for use with bucket and liner combination, as shown and described.

DESCRIPTION

This application incorporates by reference the disclosure of U.S. patent application Ser. No. 29/550,561, entitled Bucket and Liner Combination, which is being filed concurrently with the present application.

FIG. 1 is an exploded perspective view of a liner for use with bucket and liner combination according to a first embodiment of our new design, shown in combination with a bucket;

FIG. 2 is an exploded perspective view of thereof;

FIG. 3 is an assembled perspective view thereof;

FIG. 4 is an exploded front view thereof, the front view being identical to the rear view, the left side view, and the right side view;

FIG. 5 is an assembled front view thereof, the front view being identical to the rear view, the left side view, and the right side view;

FIG. 6 is a top view thereof, the top view being identical to the bottom view;

FIG. 7 is an exploded perspective view of a liner for use with bucket and liner combination according to a second embodiment of our new design;

FIG. 8 is an exploded perspective view of a liner for use with bucket and liner combination according to a third embodiment of our new design;

FIG. 9 is an exploded perspective view of a liner for use with bucket and liner combination according to a fourth embodiment of our new design; and,

FIG. 10 is an exploded perspective view of a liner for use with bucket and liner combination according to a fifth embodiment of our new design.

The broken lines in the drawings are to illustrate environment only and form no part of the claimed design.

1 Claim, 10 Drawing Sheets
